FRANK SEDIVY, OF GLOBE, ARIZONA TERRITORY.

POWER-TRANSMITTING MECHANISM.

SPECIFICATION forming part of Letters Patent No. 724,338, dated March 31, 1903.

Application filed October 2, 1902. Serial No. 125,653. (No model.)

To all whom it may concern:

Be it known that I, FRANK SEDIVY, residing at Globe, in the county of Gila and Territory of Arizona, have invented a new and Improved Power-Transmitting Mechanism, of which the following is a specification.

My invention is in the nature of an improved construction of duplex screw gear or shaft and a traveler co-operatively connected therewith for converting a continuous rotary motion into a reciprocal motion; and my invention primarily seeks to provide an improved mechanism of the character stated of a simple, economical, and stable construction, in which the operation of converting the motion is entirely automatic and positive.

Generically, my invention comprehends a rotary shaft having duplex or bisecting screw-ways in its periphery mounted in suitable bearings and provided with means whereby a continuous rotary motion may be imparted thereto mechanically or manually, stationary frame portions, a traveler suitably mounted on the screw gear or shaft, carrying independently-operable detents at each end, arranged to be alternately moved into and out of engagement with the threadways in the screw-shaft, said traveler also having attached means for transmitting its reciprocal motive power to a supplemental mechanism, and trip devices mounted upon the stationary framing for shifting the independently-operable detent devices mounted on the traveler automatically at predetermined intervals.

In its more subordinate features my invention consists in certain novel details of construction and peculiar combination of parts, all of which will hereinafter be fully explained, and specifically pointed out in the appended claims, reference being had to the accompanying drawings, in which—

Figure 1 is a side elevation illustrating my invention, with the several parts thereof especially arranged for operating an air-compressing means. Fig. 2 is a transverse section thereof, taken on the line 2 2 of Fig. 1. Fig. 3 is a longitudinal section on the line 3 3 of Fig. 2 and illustrates the preferred construction of trip devices for engaging and shifting the traveler-carried detents. Fig. 4 is a view of one of the trip mechanisms and illustrates the traveler as having reached the

limit of its movement in the direction of the arrow and the trip devices as engaging the detent to move the same into contact with the screw-gear to reverse the motion of the traveler. Fig. 5 is a cross-section on the line 5 5 of Fig. 4. Fig. 6 is a detail view of a pair of alternately-operating detents and the pivotal connecting member therefor. Fig. 7 is a detail view of one section of one of the inclined guides that form a part of the trip mechanism. Fig. 8 is a view of one of the shifting or tripper springs that co-operate with the inclined guides. Fig. 9 is a detail view of a modified form of the trip devices hereinafter explained.

In the accompanying drawings I have illustrated an operative arrangement of my motion-converting and power-transmitting mechanism; but I desire it understood that the structure shown may readily be modified and changed in detail to suit the particular purpose for which my power-transmitting and motion-converting means may be utilized without departing from my invention as set out in the appended claims.

In the drawings I have shown the screw gear or shaft 1 disposed horizontally and journaled in end portions 2 2 of a supporting-frame, which includes a number of horizontal beams 2^a 2^b, that join the ends 2 2 of the frame and which are equidistantly disposed radially about the axis of the screw gear or shaft 1.

The shaft 1 at one end has a drive-pulley 1^a or crank-handle, and at a suitable point, preferably at the other end, it has a balance-wheel 3. That part of the shaft 1 between the frame members 2 2 is in the nature of a duplex screw-gear, (designated by 2^c), which is formed by producing a duplex series of screw-threads thereon, one set of which crosses or bisects the other, as clearly shown in Figs. 1 and 3, whereby a series of continuous spiral threadways X, having a parallel pitch in one direction, and another like set of threadways Y, having a reverse pitch, are provided.

That part of the shaft 1 which projects beyond the inner frame member 2 is smooth, as indicated at 2^c, to accommodate a cross-head 4, slidable thereon, which head is utilized to transmit motive power to a supplemental mechanism. For illustration, I have

shown a pump-cylinder P, mounted in the smooth part of the shaft 1, and a piston therefore joined with the cross-head 4, whereby air may be pumped under pressure into a storage-tank T, connected with the pump-cylinder P, which latter in practice has valves suitably arranged in any well-known manner for the ingress and egress of air.

While I have shown my invention as adapted for operating an air-compressor, it is manifest the reciprocal movement of the cross-head may be utilized for various other mechanical purposes.

The cross-head 4 is joined to the traveler 5, and the latter consists of a drum mounted upon the screw-shaft 1 to freely slide thereon, and the said traveler has a series of diagonal spirally-disposed slots $a a' a^2$ at one end, the pitch of which is in the direction of 20 and parallel with the pitch of one set of threadways X in the shaft 1, and the traveler also has a similar set of slots $b b' b^2$ at the opposite end, the pitch of which is reverse to that of the slots $a a' a^2$ and in a plane parallel with the threadways Y.

In the drawings I have shown three slots in each set, such number being shown to register with the number of threadways in each set X Y on the shaft 1, it being understood 30 that if it is desired to move the traveler rapidly the shaft is made of a large diameter, while the threads are made of an increased pitch, it being obvious that in all cases it is preferred to form the opposite ends of the 35 traveler 5 with as many slots as there are spiral threads in each set of threadways on the shaft 1.

With each set of slots $a a' a^2$ and $b b' b^2$ is coöperatively joined a series of detents, one 40 for each slot, and said detents are designated by C C' C² and D D' D². It will be noticed in the drawings the slots at the opposite ends are disposed in the same longitudinal planes, such arrangement being provided for conveniently joining the opposing detents in 45 pairs—that is, the one C with the opposite one D, C' with D', and C² with D²—the connection for each pair being in the nature of a walking-beam E, centrally pivoted to a projected bifurcated bearing e, extended radially 50 from the traveler 5, and to the ends of the said beams E the oppositely-operating detents are pivotally connected, as shown.

So far as described the operation of the 55 parts is as follows: In starting the mechanism all of the beams E are tilted to pull all the detents at one end of the traveler out of engagement with their coöperating threadways, and the detents at the other end of the 60 traveler are pushed inward to engage their respective threadways, which, for example, may be the set designated by X. Rotary motion is then imparted to the screw-gear shaft 1, and the traveler 5 will be thereby caused 65 to move in the direction indicated by the arrow 10, and in thus moving the cross-head connected with the traveler transmits power

in the same direction. This movement of the traveler continues to a predetermined point, when the walking-beams E of all of the detents are tilted, and the detents in engagement with the threadways X are disengaged therefrom, and the other set of detents are moved to engage with the threadways Y, and by reason of the reverse pitch of the said 75 threadways Y the movement of the traveler will be reversed, said relative operation of the parts in the practical machine being continuous so long as the screw-gear shaft 1 is turned, by reason of the means that are provided for automatically shifting the detents at predetermined times, which means form an 80 essential feature of my invention and which I shall now proceed to describe.

In the preferred construction the detent-tripping mechanism, of which there is one for each of the detents, consists of a pair of studs 85 15, secured to and projected radially from the traveler 5. To the outer end of said studs is fixedly connected an inwardly-inclined 90 guideway, consisting of a pair of opposing members 16 16, spaced apart to form a slotway 16^a therebetween, and each of the members 16 includes a vertical or side guide-flange 16^b and a horizontal guide member 16^c, the 95 upper extremity of which is beveled, as at 16^d, and the lower portion of which is in the nature of a spring-held hinged member 16^e, adapted to yield in an upward direction, the 100 reason for which will presently appear.

Each guideway 16 is disposed in the longitudinal plane of the traveler, and the guideways at one end project from the traveler in one direction and those at the other end in an opposite direction, and each opposing pair 105 of said guideways is disposed in radial alignment with the adjacently-disposed stationary portions 2 of the supporting-frame, as clearly shown in Fig. 2.

It will be noticed from Fig. 4 the upper or 110 beveled end of each of the guideways terminates over one extremity of their coacting walking-beams E, and the ends E^x of said beams are formed with extensions e⁵, dovetailed in cross-section to coact with restraining-springs 17, each of which is provided with a pair of spring-fingers 17^a, projected radially 115 from the traveler, one set at each end of its detent-receiving slots. The spring-fingers are held to straddle the coacting ends of the 120 beams E, and they have inwardly-bent shoulders E^b, which slip under the ends of the said beams when the ends are swung outward to withdraw the detents from engagement with the screw, and thereby hold the said detents 125 positively locked to their withdrawn or inoperative position until they are again moved by the trip mechanism into an operative position.

The outer ends of the spring-fingers 17^a are 130 disposed just under the beveled upper ends of the slotted guideways, the purpose of which will presently appear.

At the inner side of each frame portion 2 2

is secured a pair of inwardly-projecting spring-arms 20^a, which are in the same longitudinal plane, but project in opposite directions. The inner ends of said springs or trip members 20 are made fast to the frame portions 2, and their outer ends are bent inwardly and terminate in slightly-upturned portions 20^b, provided with lateral studs 20^b, and the said members 20 are so arranged 5 relatively with the inclined guides that in one direction of movement of the traveler the portion 20^a thereof rides in the slotway of the guide 16 and with their studs 20^b in engagement with the upper face of the guide-flanges 16, it being understood that by reason of the incline of the guides 16 the springs 20 will be constantly moved back under increased tension until the upper beveled edge of the guides 16 is reached, when by reason of 10 the pressure on the springs 20 the ends 20^a will snap down back of the guides 16 and in their movement first engage with and spread the spring-fingers 17^a 17^b, and thereby free the coincident end of the walking-beam E, 15 which was previously held locked, and then engage the said end and force it inward to bring its detent into engagement with the screw-gear, it being understood that by reason of the pivotal connection of the beam E 20 at the same time the aforesaid end is moved inward the other end of the beam, together with its detent, will be moved outward to disengage the said other detent from the screw-gear and move the said other end of the beam 25 into a locked engagement with its co-operating spring-fingers 17^a.

On the reverse movement of the traveler the spring 20, last referred to, will slip under the inclined guide and move outwardly under the same until it moves into engagement with the lower end of said guide. The hinged portion of the guide will yield sufficiently to permit the studs 20^b of the spring end 20^a to readily slip upwardly and on the return movement of the traveler again move into engagement with the upper end of the guide-flanges 16^b.

In Fig. 9 I have illustrated a slightly-modified construction of the detent devices, the operation of which is similar to that of the preferred form described; but in the said modified form a single stud or post is projected radially from the traveler, one for each detent-receiving slot, and which is indicated by 50 25, the outer end of which is bifurcated to receive a centrally-pivoted pawl 26, which is held in engagement with the springs 20^x, which in the present construction is not equipped with lateral studs, as in the other form, and 55 one end of the pawl 26 is held to coact with the spring-fingers 17^a and the coincident end of the detent-carrying beam, and the other end of the pawl extends forward of the bifurcated bearing engaging its fulcrum. In this 60 latter form of trip devices in one direction of movement of the traveler the spring 20^x engages the pawl 26 until the bearing of said

spring is at a point inside of the fulcrum of the pawl 26, when the spring-pressure on the pawl rocks the said pawl and causes it to 70 spread the fingers 17^a to release that end of the beam E that engages the same and then press the freed end of the beam with its detent inward, the pawl at the opposite end of the beam E at this time being shifted to its 75 opposite or reverse position, as shown.

From the foregoing, taken in connection with the accompanying drawings, it is believed that the complete operation and construction of my invention will be readily understood. 80

Having thus described my invention, what I claim, and desire to secure by Letters Patent, is—

1. A mechanism of the character described, comprising, a suitable supporting-frame, a 85 continuously-rotatable screw-gear journaled therein, said gear including independent intersecting and reversely-inclined threadways, a traveler loosely slideable over the said gear, means mounted on the traveler for interlocking it with the screw-gear, said means including spring-controlled automatically-operating independent detents, one for each threadway for alternately moving into and out of engagement with the independent reversely-inclined threadways in the screw-gear, for the 90 purposes described.

2. In a mechanism as described, the combination with a continuously-rotatable screw-gear, consisting of a shaft having a series of 100 independent intersecting threadways inclined in reverse directions, a traveler reciprocally mounted on the screw-gear, detent mechanism in each end thereof for engaging the threadways in the screw-gear, the detents at 105 one end being arranged to engage one set of threadways, and the detents on the other end to engage with the other or reverse set of threadways, and spring-controlled automatically-operating trip devices for the said detents operable by the reciprocal movement of the traveler for moving the opposing detent devices alternately into and out of engagement with their respective threadways in the screw-gear, all being arranged substantially 110 115 as shown and described.

3. In a mechanism as described, the combination with the screw-gear, having a threadway X in one direction, and a threadway Y in a reverse direction, the two threadways 120 intersecting each other; of a power-transmitting traveler freely slideable on the said gear, said traveler having a slot at one end in the plane of the threadway X, and a similar slot in the other end in the plane of the threadway Y, a detent operable through each slot to co-operate with the threadways X and Y, a walking-beam mounted on the traveler, to the opposite ends of which the aforesaid detents are connected, and spring-controlled 125 automatically-operating trip mechanism for engaging the walking-beam at predetermined intervals to tilt the same, whereby to move one detent into an interlocked engagement 130

with its respective threadway on the screw-gear, and the other detent out of engagement with its threadway, for the purposes specified.

4. In a mechanism as described, the combination with the continuously-rotatable screw-gear, said gear having a threadway X running in one direction and a threadway Y intersecting the threadway X, and running in the reverse direction thereto, a power-transmitting member, a pair of oppositely-operable detents mounted thereon, one of which is arranged to coöperate with the threadway X, and the other with the threadway Y, spring-controlled automatically - operable detent mechanism for moving one detent out of engagement with its coacting threadway, and simultaneously moving the other detent into a coacting engagement with its respective threadway, for the purposes described.
5. In a mechanism as described, the combination with the screw-gear, including the intersecting threadways X and Y; of a traveler reciprocally slidable upon the screw-gear, a detent mounted on one end of the traveler

to engage the threadway X, a second detent 25 in the other end of the traveler for engaging the threadway Y, an automatically-operating tripper mechanism for simultaneously shifting the two detents in reverse directions, whereby as one detent is moved into engagement with its respective threadway, the other detent will be moved out of engagement with its coacting threadway, an automatically-operating lock device for holding the withdrawn detent to its adjusted position, the aforesaid trip mechanism being governed by the reciprocal movement of the traveler, and including a member adapted to first trip the lock device to release the withdrawn detent, and then engage the said released detent and 40 move it to its thread-engaging position, and means for joining the two detents whereby to operate them in unison, in the manner and for the purposes described.

FRANK SEDIVY.
